FIG.1

Des. 187,994
PAGE 2

FIG. 3

Fig. 1 is a front perspective view of a juvenile vehicle showing my new design;

Fig. 2 is a top plan view thereof with the pedal and steering wheel portions omitted for convenience of illustration; and

Fig. 3 is a left side elevational view thereof.

The dominant feature of my design resides in the portion shown in full lines.

I claim:

The ornamental design for a juvenile vehicle, substantially as shown and described.
